UNITED STATES PATENT OFFICE.

CHARLES S. BONNEY, OF PHILADELPHIA, PENNSYLVANIA.

PIPE-VISE.

SPECIFICATION forming part of Letters Patent No. 357,306, dated February 8, 1887.

Application filed April 26, 1886. Serial No. 200,236. (No model.)

To all whom it may concern:

Be it known that I, CHARLES S. BONNEY, a citizen of the city and county of Philadelphia, State of Pennsylvania, have invented certain 5 Improvements in Pipe-Vises, of which the following is a full, clear, and exact description, reference being had to the accompanying drawings, forming a part of this specification.

The nature and object of my invention is to 10 produce a pipe-vise which will hold a pipe or rod more firmly than those now in use, and at the same time be more simple and inexpensive; and to this end it consists in combining with either jaw of a vise composed of two jaws, 15 one or both movable on a connecting-bar, a double eccentric pivoted minor jaw, so arranged with relation to the other parts of the device that it will always adjust itself automatically to grasp the pipe or rod to be held.

20 In the drawings, Figure 1 is a side elevation of my improved pipe-vise; and Fig. 2, a section through the movable jaw and minor eccentric jaw, showing the construction and arrangement of said parts.

25 To the base B is secured the fixed jaw D, of the usual form, recessed longitudinally to fit and receive the bar A, which slides through it, and to the end of this sliding bar is secured the movable jaw H. These jaws are moved 30 toward each other by means of a screw-bar, F, and a handle, E, the screw-bar passing through journals in the said jaws, one of which is screw-threaded, as shown in Fig. 1. The movable jaw H is recessed at P, to admit one end 35 of a minor jaw, K, working on the pin M

passing through it and the movable jaw H; and back of this jaw K, and pressing against its rear end, is a flat spring, N, the tendency of which is to keep the jaw K in position shown, though it is free to swing in the slot P 40 vertically on pivot, and so adjust itself to firmly grasp the article to be held. Its outer face is in the shape of a double eccentric, and its motion under pressure due to this construction is shown in Fig. 1, its said face being serrated 45 or toothed.

The operation is such that when a pipe or rod is screwed up between the jaw D and the minor jaw K of the movable jaw H any attempt to turn the pipe in either direction will 50 cause the minor jaw K to turn on the pivot and the inclines of its face to grasp the rod or pipe with increasing firmness.

What I claim as new, and desire to secure by Letters Patent, is—

55 The combination, with the fixed jaw D and sliding jaw H, of a minor pivoted jaw, K, with its spring N, said minor jaw having a grasping-surface in the form of a double incline toward the center, said parts being constructed, 60 combined, and operating substantially as described.

In testimony whereof I have hereunto affixed my signature this 21st day of April, A. D. 1886.

CHARLES S. BONNEY.
